Inventors

UNITED STATES PATENT OFFICE.

JOSEPH E. TERRELL, WILLIAM TERRELL, AND FRANKLIN M. MONTGOMERY,
OF CLARENDON, TEXAS.

CATTLE-HOLDER.

SPECIFICATION forming part of Letters Patent No. 699,988, dated May 13, 1902.

Application filed October 21, 1901. Serial No. 79,435. (No model.)

To all whom it may concern:

Be it known that we, JOSEPH E. TERRELL, WILLIAM TERRELL, and FRANKLIN M. MONTGOMERY, citizens of the United States of 5 America, residing at Clarendon, in the county of Donley and State of Texas, have invented certain new and useful Improvements in Cattle-Holders, of which the following is a specification.

10 This invention relates to cattle-holders, and particularly to those designed for use for branding, dehorning, and the like.

15 The object of the invention is to provide novel means for confining cattle and holding them in an upright position against movement.

20 Furthermore, the object of the invention is to provide novel operating mechanism whereby pressure is exerted against the bodies of the cattle confined.

25 Furthermore, the object of the invention is to produce a holder adapted for cattle of varying sizes and in combination therewith a gate for controlling the passage through the holder, the said gate being operated from the point of operating of the holding mechanism.

30 With the foregoing and other objects in view the invention consists in the details of construction and in the arrangement and combination of parts whereby a cattle-holder is produced which will possess advantages in points of efficiency, durability, and inexpensive production, proving at the same time simple in operation.

35 In describing the invention in detail, reference will be had to the accompanying drawings, forming a part of this specification, wherein like characters denote corresponding parts in the several views, and in which—

40 Figure 1 is a perspective view of a cattle-holder embodying the invention. Figs. 2 and 3 are end views showing the parts in different positions.

45 In the drawings, 1 indicates a series of pairs of sleepers, on which the holder is supported. Between each pair of sleepers are pivoted two posts 2, slightly separated and free to swing apart with sufficient distance to admit of the

passage of the cattle therebetween. The series of posts on each side are connected by 50 the rods 3 and at the lower ends by the boards 4, which serve to confine the cattle and prevent their feet from protruding outside of the plan of the posts. Each pair of posts at the top have pivoted thereto the links 5, the ends 55 of the links being pivotally connected at the ends opposite to those which are pivoted to the post. Links 6 are pivoted to the central pair of links 5 and connect with the lever 7, which is fulcrumed between the uprights 8, 60 supported on the central sleepers.

In practice we prefer to station the holder at the end of a chute or way through which the cattle are driven and made to enter the holder, when a pull on the lever 7 will serve 65 to swing the sides of the lever toward the sides of the animal, which are compressed or squeezed to such a degree that said animal is held against movement longitudinally of the holder and its feet are confined by the 70 strips 4.

A gate 9 is pivoted at one end of the holder by means of the rails thereof at one end being pivoted between uprights 10.

The front end of the gate is elevated through 75 the medium of a flexible connection 11, which is run over a pulley 12 and terminates in the end of lever 7, in order that a single operator may manipulate the lever which operates the sides of the holder and also the connection 80 which raises the gate or allows it to descend by gravity.

It is noted that various changes in the details of construction and in the proportions may be resorted to for successfully carrying the invention into practice without departing from the scope thereof.

Having thus fully described the invention, what we claim as new, and desire to secure by Letters Patent, is—

90 In a cattle-holder, a series of posts suitably pivoted at their lower ends, a second series suitably pivoted at their lower ends and acting in conjunction with the first-named series, links pivoted to the tops of the posts 95 and pivoted together in pairs, upwardly-ex-

tending links pivoted to the intermediate pair of links, a lever for elevating and depressing the upwardly-extending links, and boards and rods connecting the posts to form 5 opposite sides whereby the movement of the intermediate posts will be conveyed to the end posts, as and for the purpose described.

In testimony whereof we affix our signa-

tures, in the presence of two witnesses, this 14th day of September, 1901.

JOSEPH E. TERRELL.

WILLIAM TERRELL.

FRANKLIN M. MONTGOMERY.
